The ornamental design for a door horizontal rail extrusion, as shown and described.

DESCRIPTION

FIG. 1 is a top perspective view of a door horizontal rail extrusion showing our new design, the door horizontal rail extrusion is broken in the center to disclose indeterminate length;

FIG. 2 is a bottom perspective view thereof;

FIG. 3 is a top perspective view of a second embodiment of the door horizontal rail extrusion showing our new design; and,

FIG. 4 is a bottom perspective view thereof.

FIG. 1

FIG. 2

FIG. 3

FIG. 4
